UNITED STATES PATENT OFFICE

ERNST RICHARD STEIN AND KARL VOLLMAND, OF KASSEL, GERMANY, ASSIGNEES TO
THE SUPERHEATER COMPANY, OF NEW YORK, N. Y.

SUPERHEATER

Application filed January 13, 1928, Serial No. 246,594, and in Germany August 20, 1927.

The invention relates to flue superheaters of the type in which the superheater elements are made of pipe lengths and have their ends secured to headers arranged in stepped formation. This type of superheater has the main advantage that the superheater elements are arranged in rows corresponding to the rows of the flues, and that the superheater elements of each row are gathered into a group whose connections to the headers are easily accessible so that the element group can conveniently be attached and detached as long as its weight is not too great. This unduly large weight of the groups occurs where boilers are of large diameter and where, therefore, a relatively large number of superheater elements lies in a row of flues. The difficulty of handling heavy groups of superheater elements has been the principal reason why the stepped form of header has not so far been used in large boilers, but that an arrangement has been adopted in such boilers whereby the elements of two adjacent rows of flues are gathered into a plurality of smaller groups, and the connections to the steam headers being so arranged that the wet and superheated steam ends alternate in a single row, and that in each row of ends for wet and superheated steam the connections of the several element groups lie one in front of the other. In this manner it is possible to obtain relatively light element groups, but the disadvantage results that the inner connections are difficult of access, and that on account of the offsets required for two neighboring element rows of superheater elements, the free areas in the smoke tubes as well as the lanes through which the gases flow are obstructed.

The invention points out one way in which these difficulties can be avoided by making it possible to use relatively light element groups, while retaining the advantages of the stepped header form. For this purpose, the superheater elements belonging to a single row of tubes are, according to this invention, subdivided into mutually independent groups lying one in front of the other, and arranged in such manner that the pipes of the superheater elements opening

into the steam headers and members connecting them to the headers all lie in the same plane. The means of securing the elements to the headers in this newly arranged element group are readily accessible. The groups are easy to manipulate. The free area of the flues remains as large as possible so that they are easy to clean, and the broad free lanes between the element rows make possible an unobstructed gas flow.

An especially advantageous form of the new superheater arrangement is obtained if the header for saturated steam and the one for superheated steam are themselves each again given a stepped form, and one of these headers is placed within the angle formed by the step of the other. In the middle, therefore, there are arranged two superheated or two saturated steam steps, while the other header which bears the two other steps encloses the inner header on the two sides of an angle. In such an arrangement the elements of the row are subdivided into two groups, and are very readily accessible for inspection, and the headers are simple in form and need no inner walls.

In the drawing there are shown by way of illustration two forms of the new superheater arrangement in connection with a locomotive boiler. Fig. 1 shows a vertical section through the superheater headers and through a tier of flues, the superheater elements being shown in a lateral elevation; Fig. 2 shows a few superheater element groups connected to the headers, and Fig. 3 shows a front view of the superheater headers. In Fig. 2, the ends of the elements leading to the headers from the two lower right elements are cut away so that the view will show more clearly the arrangement of the several loops forming the elements.

Figs. 4 and 5 show a second form of the invention, and are views corresponding to Figs. 1 and 3 respectively.

In the form of our invention according to Figs. 1 to 3, 10 designates the flue sheet, and 11 the flues of the locomotive boiler, 12 refers to the several superheater elements, 13 to the saturated steam header, and 14 to the superheated steam header. Each

of the two steam headers is angular in cross-section, and is provided with two connection surfaces lying in forwardly stepped relation to each other. The connection surfaces 5 of the saturated steam header are designated by 13^a and 13^b, and the connection surfaces of the superheated steam header by 14^a and 14^b. The superheated steam header 14 lies in the angle of the saturated steam header 13 so that from front to back the stepped connection surfaces occur in the following order: step 13^a of the saturated steam header; step 14^a of the superheated steam header; step 14^b of the superheated steam header; and step 13^b of the saturated steam header. Saturated steam flows to the saturated steam header 13 through the central connection 15. The superheated steam is carried away from the superheated steam 20 header 14 through the two lateral outlets 16. For the purpose of connecting the superheater elements to the superheater headers, two intermediate chambers 17 and 18 are used to which the superheater elements are welded. These intermediate chambers are connected to the superheater headers in the usual way by means of clamps 19 and studs 20.

As may be seen from Figs. 1 and 2, a 25 vertical row of flues contains six superheater elements which are subdivided into two groups, each containing three elements. If, for example, the arrangement of the element 12^a is considered, it will be seen that 30 the end connected to the rear intermediate chamber 17 of the saturated steam header 13 is carried downward in the vertical plane in which the connections of said element lie is then bent laterally by the amount by 35 which the two straight portions of the loop are separated from each other (see offset 12' in Fig. 2), is then looped in U-shape into the flue and again into the flue below, next extends forward a distance, is then laterally bent back to the connection plane, and in this plane bent upward to the rear intermediate chamber 18 of the superheated steam chamber 14. In this manner the pipe 40 lengths of the superheater elements of a row leading from and to the headers as well as their connections to the headers all lie in the same plane.

The illustrative form according to Figs. 4 and 5 shows a variation in the shape and 45 arrangement of the superheater headers. While the headers are here also angular, and each with two connection surfaces, the saturated header 21 is here placed into the angle of the superheated header 22. The central admission connection 23 to the saturated steam header 21 extends through a cored opening of the superheated header 22. In addition, there is arranged at the top of the superheated steam chamber and unitary 50 60 65 70 75 80 85 90 95 100 105 110 115 120 125 130 135 140 145 150 155 160 165 170 175 180 185 190 195 200 This multiple throttle is of a known form and controls the flow of the superheated steam from the superheated steam chamber proper to the steam pipe connections 27. The sub-division of the superheater elements into two groups, the shape of the pipe lengths forming the elements and extending from the headers, and the connection of the elements to the headers corresponds exactly to the form of the invention first described.

By the sub-division of the elements belonging to a tier of flues into two groups independent of each other, the weight of a single group remains so low even with boilers of large diameter that the element can be handled without difficulty. The elements gathered into a group can be safely welded into the intermediate chambers, and these can be reliably secured to the headers. The connection members are easily accessible so that removal and re-insertion of the element groups can be easily performed since the ends of the superheater elements leading from and to the headers all lie in a single plane.

We claim:

1. A flue superheater with headers in stepped relation characterized by the fact that the superheater elements associated with each row of flues are connected to form independent groups one in front of the other and are so arranged that the pipe lengths of the elements of one row leading from and to the headers all lie in a single plane.
2. A flue superheater according to claim 1, characterized by the fact that the stepped surfaces of the headers to which the elements are connected are subdivided into a plurality of steps corresponding to the number of groups of elements.
3. In apparatus of the class described, the combination of a vertical row of flues; a bi-chambered header above and forward of the flues, the front walls of each chamber being stepped and one of the chambers lying within the angle of the other; four intermediate chambers in the flue plane and secured to the four front header surfaces and communicating with the interior; and two superheater element groups, each element comprising a plurality of loops extending into adjacent flues one loop to a flue, the two ends of each of the several elements of the upper group being connected to the two intermediate chambers nearest the flues, and the two ends of each of the several elements of the lower group being connected to the two intermediate chambers furthest from the flues.

The illustrative form according to Figs. 4 and 5 shows a variation in the shape and arrangement of the superheater headers. While the headers are here also angular, and each with two connection surfaces, the saturated header 21 is here placed into the angle of the superheated header 22. The central admission connection 23 to the saturated steam header 21 extends through a cored opening of the superheated header 22. In addition, there is arranged at the top of the superheated steam chamber and unitary with it, the housing 25 for the throttles 26.

group being connected to the two intermediate chambers farthest away from the flues.

4. Apparatus according to claim 3, wherein in the two legs of each loop lie in a horizontal plane and the intermediate chambers lie in a plane with one vertical row of the legs.

5. Apparatus of the class described comprising two adjacent sets of flues and superheater elements according to claim 3, the two legs of the loops lying in horizontal planes, the intermediate chambers of the two sets lying in the planes of the outside legs; clamps engaging the intermediate chambers; and screw means between the pairs of intermediate chambers pulling the clamps toward the headers.

6. A flue superheater with headers in stepped relation, one of which headers is of angular formation, characterized by the fact that the superheater elements associated with each row of flues are connected to form independent groups one in front of the other and are so arranged that the pipe lengths of the elements of one row leading from and to the headers and their connections to the headers all lie in a single plane, said flue superheater being further characterized by the fact that one of said headers is located within the angle formed by the step of the other.

30 7. A flue superheater according to claim 6, characterized by the fact that the stepped surfaces of the header are subdivided into a plurality of steps corresponding to the number of groups of elements.

35 8. A flue superheater with a saturated steam chamber and a superheated steam chamber in stepped relation, one of said chambers being of angular formation, characterized by the fact that the superheater elements associated with each row of flues are connected to form independent groups one in front of the other and are so arranged that the pipe length of the elements of one row leading from and to the chambers and their 40 connections to the chambers all lie in a single plane, and said superheater being further characterized by the fact that one of said chambers is located within the angle formed by the step of the other.

45 9. A flue superheater according to claim 8 characterized by the fact that the connection to the steam chamber lying in the angle formed by the step of the other chamber extends through a hollow in the other chamber.

50 10. A flue superheater with headers and saturated steam chamber and superheated steam chamber in stepped relation, one of said chambers being of angular formation, characterized by the fact that the superheater elements associated with each row of flues are connected to form independent groups one in front of the other and are so arranged that the pipe lengths of the elements of one row leading from and to the chambers and their 55 connections thereto all lie in a single plane,

the stepped surfaces of the header being subdivided into a plurality of steps corresponding to the number of groups of elements, one of the aforementioned chambers being located within the angle formed by the step of the other, and extending through a hollow in said other chamber.

70 In testimony whereof we affix our signatures.

ERNST RICHARD STEIN. 75
KARL VOLLAND.
